UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A COAT.

Application filed August 6, 1924. Serial No. 10,394. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Coat, of which the following is a specification, reference being had to the accompanying drawing, forming part thereof, wherein the coat is distinguished by means of a collar and an edging of fur on each of the front edges having laterally extending stripes matching the stripes on the cuffs.

In the accompanying drawing—

Figure 1 is a perspective view of a coat, showing my new design.

Figure 2 is a perspective view of the coat shown in Figure 1 but showing the coat thrown open for illustrating more fully the ornamental effect of the fur edging.

I claim:

The ornamental design for a coat, substantially as shown and described.

TAUBE DAVIS.
